Leslie W. Ferguson, Smithwick, S. Dak.

Application February 28, 1956, Serial No. 40,394

Term of patent 14 years

(Cl. D33—3)

FIG. 1

FIG. 2

FIG. 3

FIG. 4

FIG. 5

Fig. 1 is a front elevational view of a rifle rack showing my new design; the broken line indication of a rifle being for illustrative purposes only;

Fig. 2 is a front elevational view of the rifle rack with the tip receiving member being shown in its open pivoted position;

Fig. 3 is a top plan view of the design as seen from the top of Fig. 1;

Fig. 4 is an enlarged left end elevational view of Fig. 1; and

Fig. 5 is an enlarged right end elevational view of Fig. 1.

Those portions shown in full lines constitute the dominant features of the design.

I claim:

The ornamental design for a rifle rack, substantially as shown and described.
